US00D817935S

(12) **United States Design Patent** (10) **Patent No.:** **US D817,935 S**
Zukowski (45) **Date of Patent:** **** May 15, 2018**

(54) **NOISE MITIGATING MICROPHONE ATTACHMENT**(71) Applicant: **Kaotica Corporation, Corporation #2015091974**, Calgary (CA)(72) Inventor: **Konrad Zukowski**, Calgary (CA)(73) Assignee: **KAOTICA CORPORATION, CORPORATION # 2015091974**,
Calgary (CA)(**) Term: **15 Years**(21) Appl. No.: **29/585,882**(22) Filed: **Nov. 29, 2016****Related U.S. Application Data**

(60) Division of application No. 29/471,259, filed on Oct. 30, 2013, now Pat. No. Des. 733,690, which is a continuation of application No. 29/532,371, filed on Jul. 6, 2015.

(51) **LOC (11) Cl. .... 14-01**(52) **U.S. Cl.**USPC ..... **D14/228**(58) **Field of Classification Search**USPC D14/203.1, 203.6, 204–207, 210–221,

Primary Examiner — Susan Bennett Hattan*Assistant Examiner* — Marie D Fast Horse(74) *Attorney, Agent, or Firm* — Kilpatrick Townsend & Stockton LLP(57) **CLAIM**

The ornamental design for noise mitigating microphone attachment, as shown and described.

DESCRIPTION

FIG. 1 is a front elevational view of a noise mitigating microphone attachment showing my new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof; and,

FIG. 7 is a right, front perspective view thereof.
